US00D595594S

(12) **United States Design Patent**
Garcia

(10) **Patent No.:** **US D595,594 S**
(45) **Date of Patent:** **** Jul. 7, 2009**

(54) **TIME DISPLAY**

(76) Inventor: **Christopher George Garcia**, 1214
Cypress Dr., Richardson, TX (US) 75080

(**) Term: **14 Years**

(21) Appl. No.: **29/322,124**

(22) Filed: **Jul. 29, 2008**

(51) **LOC (9) Cl.** **10-01**

(52) **U.S. Cl.** **D10/1; D10/24**

(58) **Field of Classification Search** **D10/1-29;**
368/276, 285, 316, 317, 239-242, 82-84;
368/29, 30; D11/131
